FABRIC AND METHOD OF MAKING THE SAME

Alfred L. Helwith, Larchmont, N. Y.

Application April 11, 1933. Serial No. 665,526

9 Claims. (Cl. 139—426)

This invention relates to textile fabrics and methods of making the same.

One object of the invention is to provide a textile fabric of uniform color having improved means for producing an optical rib, tension rep or bengaline effect thereon, which effect shall be mainly visual, the fabric having a smooth ribless surface and being preferably of relatively uniform or conventional weave.

10 Another object of the invention is the provision of an improved method for producing a textile fabric as above referred to.

Other objects of the invention and advantages thereof will become apparent as the specification 15 proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

25 Figure 1 is a considerably magnified plan view of a section of a textile fabric embodying the invention.

Fig. 2 is a plan view of a section of the textile fabric showing the normal appearance thereof.

30 Fig. 3 is a magnified plan view of a section of a textile fabric showing a modification of the invention.

The advantages of the invention as here outlined are best realized when all of its features 35 and instrumentalities are combined in one and the same structure, but, useful devices may be produced embodying less than the whole.

It will be obvious to those skilled in the art to which this invention appertains, that the same 40 may be incorporated in several different constructions. The accompanying drawing, therefore, is submitted merely as showing the preferred exemplification of the invention.

Referring in detail to the drawing, 10 denotes 45 a section of a textile fabric embodying the invention. The same may be constructed of a suitable weave and is of uniform color, and has a surface that is smooth in the sense that it is free of any mechanical ribs such as may be produced by 50 a special weave. Nevertheless, the fabric is characterized by a rib appearance as shown at 11, whereby the value of the fabric is enhanced. This rib appearance which is purely optical in nature as hereinafter more particularly described, is 55 perfectly uniform and neat, and may extend either across the warp 12 or the weft 13, according to the construction of the fabric, but is preferably arranged to extend transversely of the warp, and will be so referred to hereinafter, in describing 60 an illustrative embodiment of the invention.

The rib effect produced according to my invention is obtained by utilizing alternate warp 65 yarns 12a and 12b of lustrous and lusterless yarns respectively. In the drawing the lustrous yarns are indicated by the shading to differentiate from the lusterless yarns which have a flat appearance. The weft or filling yarns may or may not have lustre, as desired, but the most pronounced effect is produced by using a lusterless weft. The warp and weft yarns are of the same color and may 70 consist of the same material, and at least the warp yarns consist of one material, whereby the texture, softness, and appearance of the material are improved, and their adaptability for inexpensive manufacture into a fabric enhanced. 75 They are preferably also of the same weight and character, and may or may not have twist.

It will be noted that according to my invention, the ribbed effect 11 extends transversely of the lustrous and lusterless yarns, and as in this case, 80 crosswise of the warp. The reason for this is difficult to perceive, although it is noted that the rib effect is apparently caused by the difference in light reflection between the lustrous and lusterless warp yarns, or by an interplay between 85 the light effects of these yarns, and hence is denominated an optical ribbed effect.

For the purpose of more specifically indicating an embodiment of the invention to which the same is particularly adapted, I have devised this 90 invention for especial application to rayon fabrics or other fabrics made of a composition material. The yarns of such fabrics are plain and untwisted, and the warp yarns 12a may be lustrous while the warp yarns 12b may be lusterless or de-lusterized in any well known manner. Similarly, 95 the weft yarns may preferably be lusterless, and the warp and weft yarns may be precisely the same in color. It will be particularly noted that since the yarns of which rayon is produced are 100 substantially wholly free of twist, such characteristic could not in any way be utilized to produce a rib effect.

It may be noted that rayon yarn usually possesses a twist of between 2½ to 5 times per inch. 105 This twist however, is too slight to have any effect on the appearance of the fabric, as will be perceived by comparison with any moderately twisted cotton yarn, whose twists range between 18 and 25 times per inch. Consequently, rayon yarn 110 may for the purposes of this invention be regarded as free of twist, unless otherwise stated, although there are special rayon yarns which are free of any twist whatever.

It will be noted that the optical ribbed effect in 115 a smooth unicolor textile fabric is produced by reason of arranging the lustrous and lusterless yarns not only in alternation but in consecutive alternation; in other words, the order of the lustrous and lusterless yarns is in a one to one 120

ratio. If any larger ratio is used, as, for example, a two to two ratio the optical ribbed effect becomes indistinct, so that such would not fulfill the objects of the invention.

5 The invention may also be embodied in a cotton fabric wherein the warp yarn 12a would indicate a mercerized cotton yarn, and the warp yarn 12b, and preferably also the weft yarn, an unmercerized or plain cotton yarn. The mercerized yarn 10 may be of single or double ply, and I have found that in order to obtain a pronounced optical rib effect according to the principle above disclosed, the mercerized cotton yarn must be double ply. Such double ply yarn may be twisted in the conventional manner. The weft yarn may be single or double ply, the former being sufficient. The optical ribbed effect, however, is caused wholly by the fact that the mercerized and unmercerized yarns are lustrous and lusterless, respectively.

15 Another possible embodiment of this invention is to produce a fabric 10 having yarns 13 and 12b of cotton, and yarns 12a of cotton impregnated or coated with any material such as a cellulose material, as, for instance, that of which rayon 25 is made, in order to impart a luster to such yarn.

20 In Fig. 3 is shown a modified smooth unicolored fabric 14, such as rayon, having weft yarns 15 and warp yarns 16, 17. All of these yarns may have the same luster or lack of luster, the warp 30 yarns 17 being twisted and the warp yarns 16 being untwisted or plain straight yarns. The yarns 16 and 17 are arranged in consecutive alternation. The weight and spacing of all the yarns 15, 16, and 17 may be of a suitable nature. 35 This textile fabric affords a ribbed effect 11 as shown in Fig. 2, transversely of the warp, but this ribbed effect is much less pronounced than that of the fabric 10. Another advantage of the fabric 10 over the fabric 14 is that the latter is considerably more expensive than the fabric 10 because the rayon yarns 17 must be twisted, whereas they are produced in plain untwisted form. However, the optical ribbed effect may be 45 markedly accentuated by making one of the yarns 16, 17 lustrous and the other lusterless.

50 The method of weaving the fabric may be a conventional one, the distinguishing feature of the invention being the step of arranging of lustrous and lusterless yarns in consecutive alternation.

55 Heretofore it has been known to produce ribbed and stripe effects by using twisted yarns variously arranged. In this invention the element of twist is not utilized, but a fabric, such as a rayon fabric, is provided with an optical ribbed effect transversely of the warp by employing merely alternately consecutive lustrous and lusterless warp yarns.

60 It will be appreciated that various changes and modifications may be made in the device as shown in the drawing, and that the same is submitted in an illustrative and not in a limiting sense, the scope of the invention being defined in the following claims.

65 I claim:

1. A rayon textile fabric having an optical ribbed effect and having opposite smooth surfaces and an evenly woven warp and weft consisting of yarns of the same color, the yarns of the warp being of a uniform material and weight, the weft yarns being lusterless, and the warp having lustrous and lusterless yarns sub-

stantially free of twist and arranged in alternate single succession for producing said optical ribbed effect transversely of the warp.

2. A rayon textile fabric having an optical ribbed effect having its opposite surfaces smooth so as to be free of ribs and having a warp and a weft consisting of unicolored yarns of substantially the same uniform material and weight, the warp consisting of parallel lustrous and lusterless yarns substantially free of twist and arranged in alternate single succession throughout the fabric to cause an action of light producing the optical ribbed appearance.

3. A regularly woven textile fabric having a warp and a weft, the warp consisting of parallel alternate singly successive yarns of lustrous and lusterless yarn, said fabric and the warp and weft yarns being of uniform color and substantially free of twist, and said yarns being substantially the same weight and appearance, and the fabric being characterized by an optical ribbed effect produced by the lustrous and lusterless yarns thereof.

4. A textile fabric of a single color, characterized by an optical ribbed effect, and having a warp and a weft relatively evenly woven so that the fabric has smooth surfaces, said warp and weft being of uniform color and character, said weft consisting of lusterless yarns and said warp having alternate successive lustrous and lusterless yarns, whereby said optical ribbed effect is produced.

5. An optically ribbed textile fabric having smooth unicolor surfaces and having a warp element and a weft element, one of said elements consisting of parallel alternate lustrous and lusterless unicolored yarns of the same weight and singly successively arranged to produce the optical ribbed effect, and said fabric having a regular weave.

6. An optically ribbed textile fabric having smooth unicolor surfaces and having parallel lustrous and lusterless unicolored yarns of uniform character arranged in single succession to produce the optical ribbed effect, and said fabric having other lusterless yarns of the same nature as the first mentioned yarns, interwoven with the latter and extending at a angle thereto, whereby said optical ribbed effect is emphasized.

7. An optically ribbed textile rayon fabric having a warp and a weft, said warp consisting of parallel alternate lustrous and lusterless yarns in single succession and of uniform color for producing the optical ribbed effect transversely of the fabric, said warp and weft yarns being of the same weight and material.

8. A unicolored smooth textile rayon fabric having an optical ribbed effect and consisting of yarns of uniform color and free of twist, said fabric having a weft and a warp, the latter consisting of parallel lustrous and lusterless yarns in alternate consecutive arrangement and being of the same weight, and said fabric having a regular weave.

9. A regularly woven optically ribbed textile fabric having a warp consisting of parallel lustrous and lusterless unicolored yarns disposed in alternate single succession continuously throughout the fabric, said fabric having warp and weft yarns of the same color and appearance in texture.

ALFRED L. HELWITH.
